UNITED STATES PATENT OFFICE

IRA FINGERMAN, OF CHICAGO, ILLINOIS

SHOE HOLDER

Application filed August 1, 1930. Serial No. 472,262.

This invention relates to a shoe holder and an object is the provision of a device of this character which is compact and light in structure, economical to manufacture, and durable in use. A further object is to provide a shoe holder having shoe receiving pockets of special formation, which serve to retain shoes in their original shape, and thus restore the shoes to their proper shapes between periods 10 of wearing. A further object is the provision of a shoe holder which may be conveniently folded into compact form for traveling or packing when not in use.

Other objects will appear hereinafter. The invention consists in the combinations and arrangements of parts hereinafter described and claimed.

The invention will be best understood by reference to the accompanying drawing forming a part of this specification, and in which:

Fig. 1 is a front elevational view of the preferred embodiment of the invention in folded position;

Fig. 2 is an enlarged elevational view in operative position, with one of the shoe pockets cut away;

Fig. 3 is a cross-sectional view of the device taken substantially on the line 3-3 of Fig. 2; and

Fig. 4 is a vertical sectional view taken substantially on the line 4-4 of Fig. 2.

As illustrated in the drawing, the preferred embodiment of the device comprises a backing member 6 which, as shown in Fig. 4, is preferably composed of two flat pieces 7 and 8. These pieces may consist of any suitable material, but preferably are formed of cardboard or an equivalent material which is slightly resilient. By providing two backing pieces 7 and 8, a fabric or textile covering 9 for the backing piece 7 may be folded over the bottom and side edges as shown before stitching, and correspondingly a textile or fabric covering 10 is applied to the back piece or member 8. In the preferred structure shown, the coverings 9 and 10 are composed of a single piece of material with a transverse loop 11 formed across the upper edge of the backer for the reception of the

transverse portion of a wire holder 12 provided with a hook 13 for conveniently hanging the article on a pole 14 or elsewhere. The backer is stitched transversely to form the loop 11 and then the side and bottom edges are stitched to secure the pieces 7 and 8 and the covering material together to complete the backer and hanger. Before the backer is assembled in this manner, however, a plurality of shoe pockets 15, 16, 17 and 18 are stitched through the covering material, and the adjacent pieces 7 and 8 of the respective sides of the backer.

As shown, the pockets, which are preferably stitched so as to conceal the stitching, are formed in contour or outline to correspond with the shoe to be received. Thus pocket 15 shown in Fig. 2, is intended to receive the shoe of a right foot, pocket 16 the shoe of a left foot, pocket 18 which is opposite pocket 16, the shoe of a right foot, and pocket 17 opposite pocket 15, the shoe of a left foot.

Also as shown, the lower end 19 of each pocket is open so as to prevent the collection or deposit of dirt in the pockets, and each pocket is tapered downwardly not only to conform to the general outline of the shoe, but to cause the toe portion 20 of a shoe as shown in Fig. 4, to be straightened in such manner that the sole of the shoe will lie substantially flat against the backer and thus tend to restore the shoe to its original flat shape with the toe portion straightened while the shoe is retained in the holder. The backer, as stated, is preferably composed of a slightly resilient material such as cardboard or the like, which contributes to the lightness and compactness of the device, and when using this character of backer, it is preferable to dispose shoes on opposite sides of the backer, so that the tendency of the toe portion to bend the backer from vertical position will be equalized and the backer maintained in flat position. Thus, if but one pair of shoes is inserted, it is preferable to insert a left shoe on one side of the backer, and a right shoe in the pocket directly opposite.

In general use, it has been found that but three sizes are necessary to accommodate all

standard sizes of shoes, one size for children's shoes, one for ladies' shoes, and one for men's shoes. A flexible fabric or textile material for the pockets has been found especially 5 desirable because of the flexibility and capacity to properly straighten the shoe without injury as well as the property of being folded into compact form, as shown in Fig. 1.

While I have illustrated and described the 10 preferred form of construction for carrying my invention into effect, this is capable of variation and modification without departing from the spirit of the invention. I, therefore, do not wish to be limited to the precise 15 details of construction set forth, but desire to avail myself of such variations and modifications as come within the scope of the appended claims.

Having described my invention, what I 20 claim as new and desire to secure by Letters Patent is:

1. A shoe holder of the character described, comprising a backing member composed of a slightly resilient board, and a plurality of 25 shoe receiving pockets secured to said backing member, said pockets being composed of flexible cloth fabric and formed to taper downwardly and opening at their lower ends, and said pockets being of sufficient length 30 to engage the entire toe and instep portion of a shoe and press the toe portion against said backing member, whereby the toe portion of a received shoe is straightened with the sole held substantially flat against said 35 backing member.

2. A shoe holder of the character described, comprising a backing body composed of a board, a plurality of shoe receiving pockets secured to said backing body, said pockets 40 being composed of flexible cloth fabric and formed to taper downwardly and opening at their lower ends, and said pockets being of sufficient length to engage the entire toe and instep portion of a shoe and press the toe 45 portion against said backing member, whereby the toe portion of a received shoe is straightened with the sole held substantially flat against said backing body, and a fabric covering on both sides of said backing body 50 and being stitched to provide a transverse loop portion at the upper edge of the body for receiving a hanger.

3. A shoe holder of the character described, comprising a backing body composed of 55 board material, and a plurality of shoe receiving pockets secured in opposed abutting relation on said backing body on the opposite sides thereof, said pockets being composed of flexible cloth fabric and formed to 60 taper downwardly and opening at their lower ends, and said pockets being of sufficient length to engage the entire toe and instep portion of a shoe and press the toe portion against said backing member, whereby the toe 65 portion of a received shoe is straightened with

the sole held substantially flat against said backing body, and whereby the straightening effect on opposite sides of said backing body is equalized.

In testimony whereof I have signed my 70 name to this specification.

IRA FINGERMAN.
